COMBINED HANGING PLANTER AND DETACHABLE SAUCER THEREFOR

Ted Dziewulski, Bartlett, Ill., assignor to Phillips
Petroleum Company, Bartlesville, Okla.

Filed May 14, 1975, Ser. No. 577,499

Term of patent 14 years

Int. Cl. D11—02

U.S. Cl. D11—148

FIG. 1

FIG. 2

FIG. 3

FIG. 4

FIG. 5

FIG. 6

FIG. 7

FIG. 8

FIG. 9

FIG. 10

FIG. 1 is a top plan view of a combined hanging planter and detachable saucer therefor, showing my new design;

FIG. 2 is a bottom plan view of the planter thereof, disclosed for clarity of illustration;

FIG. 3 is an elevational view as seen from the left of FIG. 1;

FIG. 4 is an elevational view in cross section taken along line 4—4 of FIG. 1;

FIG. 5 is a top plan view of the detachable saucer, disclosed for clarity of illustration;

FIG. 6 is a bottom plan view of the detachable saucer of FIG. 5;

FIG. 7 is a side elevational view of the detachable saucer of FIG. 5;

FIG. 8 is an elevational view in cross section taken along line 8—8 of FIG. 5;

FIG. 9 is a perspective view of the hanging planter and saucer combination in an assembled condition, and provided with two cords and an S hook or the like for

securing the combined hanging planter and detachable saucer therefor in a hanging position;

FIG. 10 is an enlarged fragmentary cross sectional view of the detachable hanging planter and saucer therefor.

I claim:

The ornamental design for a combined hanging planter and detachable saucer therefor, as shown and described.
